R. M. WESTON

SHINGLE

Filed Jan. 19, 1923

Witness:

Red C. Fischer.

By

F. G. Fischer,

Attorney.

Robert M. Weston,

UNITED STATES PATENT OFFICE.

ROBERT M. WESTON, OF KANSAS CITY, MISSOURI.

SHINGLE.

Application filed January 18, 1923. Serial No. 613,618.

To all whom it may concern:

Be it known that I, ROBERT M. WESTON, a citizen of the United States, residing at Kansas City, in the county of Jackson and State of Missouri, have invented certain new and useful Improvements in Shingles, of which the following is a specification.

My invention relates to new and useful improvements in shingles and one object is to provide shingles which may be cut from sheets of pliable composition roofing or other suitable material at a minimum of waste and interlocked without weakening them with slits so common to many other types of composition shingles.

A further object is to provide shingles with elements which may be so interlocked that the wind cannot get beneath the shingles and blow them from the roof, and are so shaped that the shingles in a lower course constitute gages which enable the shingles in an upper course to be quickly installed in a uniform manner so that the finished work will be symmetrical and neat in appearance.

A further object is to provide shingles which may be installed with a minimum number of nails and labor, and in order that the invention may be readily understood, reference will now be had to the accompanying drawing, in which:

Fig. 1 is a plan view of a plurality of rows of shingles as they appear when cut from a sheet of roofing material.

Fig. 2 is a plan view showing the manner in which the shingles overlap and interlock when installed on a roof.

Fig. 3 is a detail view of one of the shingles.

Each shingle comprises a body 2 having upper and lower margins 14 and 16 respectively, an oblong pair of upper extensions 4 projecting laterally from the opposite sides of said body 2, elements 6 projecting from the upper portion of the extensions 4, and a pair of lower extensions 8 having parallel sides and projecting laterally from opposite sides of the lower portion of the body 2.

Each upper lateral extension 4 is, approximately, equal in width to one-half the width of the body 2 and in height to the intervening space 18 between it and the adjacent lower extension 8, and its upper margin 10 slopes downwardly and outwardly on an angle corresponding to the slope of the upper margin 12 of each lower lateral ex-

tension 8, the lower margin of which slopes upwardly to correspond with the sloping upper margin of each element 6, so that there will be no waste between said margins when the shingles are cut from a sheet of composition.

The lower lateral extensions 8 are spaced beneath the upper extensions 4 to leave the intervening recesses 18, hereinbefore referred to and which are of sufficient height 65 to freely admit the extensions 8 of companion shingles of an upper course when applied to a roof, as disclosed by Fig. 2.

Each lower extension 8, is approximately, equal in length and width to one half 70 the length and width of each upper extension 4 and slightly less than the length of each space 18 in order to readily enter the recesses of the adjoining shingles when the shingles are being applied to a roof, as hereinafter described.

The shingles may be applied to a roof as follows: The lower course of shingles A are trimmed off adjacent to the lower ends of the recesses 18 and are secured to the roof K 80 with the lower margins on a line with the eaves L by driving a nail through each upper extension 4. When applying the first course of shingles A as stated, the adjacent vertical margins of the upper extensions 4 85 are placed side by side and thus form a gage in spacing the bodies 2 of said course apart to admit the bodies of the second course of shingles B, which are applied by slightly bowing each shingle so that its 90 lower lateral extensions 8 can be slipped beneath the bodies 2 of the two adjacent shingles in the course A, the extensions 4 of which are covered by the bodies of the shingles in the course B. The third course 95 D, and all following courses are then applied in a like manner.

The elements 6 project far enough beneath the overlapping course to assist the upper margins 14 of the shingles to retain their 100 position from beneath the extensions 4 of said overlapping course, and owing to the manner in which the extensions 8 interlock with the shingles of a lower course all of the shingles combine to provide a cover of double thickness which is reliably held upon the roof by a nail driven through each extension 4 at the time the shingles are applied so that said nail will be protected from the weather by each upper course.

From the foregoing description it will be readily understood that I have provided a shingle embodying the advantages above pointed out, and while I have shown and 5 described the preferred form of said shingle I reserve the right to make such changes as properly fall within the spirit and scope of the claims.

Having thus described my invention, what 10 I claim and desire to secure by Letters Patent, is:

1. A shingle consisting of an oblong body, extensions projecting laterally from opposite sides of the upper portion of said body and 15 each approximately equal in width to one half the width of said body, elements projecting upwardly from said extensions, and extensions projecting laterally from opposite sides of the lower portion of said body 20 and of approximately one half the length and width of said upper extensions beneath which they are spaced to leave intervening recesses of such proportions that when two shingles in a lower course are laid side by 25 side with the vertical margins of the two adjacent upper sections abutting each other

the two adjoining recesses will admit the lower portion of the body of a shingle in an upper course and permit the lower extensions on the last-mentioned shingle to be 30 placed beneath the bodies of the two first-mentioned shingles.

2. A shingle consisting of an oblong body, extensions having sloping upper margins and projecting laterally from opposite sides 35 of the upper portion of said body and each equal in width to one half the width and slightly less than one half the length of said body, and extensions projecting laterally from opposite sides of the lower portions of said body and of approximately one half the length and width of said upper extensions beneath which they are spaced to leave intervening recesses of slightly greater 40 length than the length of said lower extensions, the upper margins of which latter slope downwardly to correspond with the sloping upper margins of said upper extensions.

In testimony whereof I affix my signature. 50

ROBT. M. WESTON.
